ANTENNA SWITCHING SYSTEM

Charles A. Rosencrans, Haddonfield, N. J., assignor to Radio Corporation of America, a corporation of Delaware

Application June 23, 1945, Serial No. 601,127

2 Claims. (Cl. 250—13)

1

This invention relates to radio systems, and more particularly to means for operating a radio transmitter and a receiver with a common antenna system. In some radio systems, particularly those of the type which radiate signals comprising short pulses and receive said signals after reflection by a remote object, it is desirable to use a single antenna system rather than to provide separate antennas for transmission and reception. In order to prevent damage to the receiver during transmission, and useless dissipation of power, it is necessary to provide means for electrically isolating the receiver from the transmitter.

It is the principal object of the instant invention to provide an improved method of and means for isolating the receiver from the transmitter in systems of the described type.

The invention will be described with reference to the accompanying drawing, of which Figure 1 is a schematic diagram of a pulse radio system embodying the invention, and

Figure 2 shows a modification of Figure 1. Similar reference characters are applied to similar elements in the drawings.

Various systems exist for isolating the receiver from the transmitter to enable use of a common antenna. A typical prior art system involves one or more spark gaps, glow tubes, or other discharge devices arranged to break down (i. e. conduct) in response to output from the transmitter. The change in impedance of the discharge device effects transfer of the antenna connection from the receiver to the transmitter.

In accordance with the present invention, the necessary switching is not provided in response to the transmitter output, but is effected by means of a control voltage, which may be conveniently obtained from the modulation input to the transmitter.

Referring to the drawing, a radio transmitter 1 is connected through a transmission line 3 to an antenna 5. The transmitter 1 includes a modulation input circuit, which is connected to a pulse source 7.

A branch transmission line 9 is connected to the line 3 at a point 11. The location of the point 11 on the line 3 is not particularly important, and the line 3 may be of any convenient length. The branch line 9, however, preferably has a length of substantially one quarter wavelength, or an odd integral multiple thereof.

The line 9 terminates in a resonator 13 which in the present illustration comprises a cylindrical outer conductor 15 and a pair of coaxial inner

2

conductors 17 and 19, connected to the respective ends of the outer conductor 15 by discs 21 and 23. A pair of smaller discs 25 and 27 may be provided at the adjacent inner ends of the inner conductors 17 and 19.

The inner conductor of the line 9 extends into the resonator 13 in a loop 29 to a point 31 on the outer conductor 15. The loop 29 provides coupling to the inner conductor 19 from the line 9.

A detector 34, such as a crystal or other contact rectifier, is connected to a point 37 on the inner conductor 17 and to a load 35 passing through a hole in the outer conductor 15. The lead 35 extends to an amplifier and an indicator or other utilization means, not shown. A load resistor 38 is connected from the lead 35 to the outer conductor 15.

A discharge tube 39, comprising a generally cylindrical glass envelope filled with a readily ionizable gas such as neon, is provided within the inner conductors 17 and 19, across the gap between the adjacent ends of said conductors. The tube 39 is provided with a pair of electrodes 40, 42, one of which is connected to a contact disc or plug 41 in the inner conductor 17. The other electrode 42 of the tube 39 is connected through a wire 43 to the pulse source 7.

In the operation of the described system, the resonator 13 acts like a low-loss parallel resonant circuit, presenting its maximum resonant impedance between the adjacent ends of the inner conductors 17 and 19. The discs 25 and 27 function as a shunt capacitor, and their principal effect is to lower the resonance frequency, so that the resonator structure may be made smaller for a given frequency than it would be if they were omitted.

The impedance presented to the line 9 by the loop 29 is also resonant owing to coupling to the resonator, but is relatively low and may be approximately equal to the surge impedance of the line 9 when the tube 39 is non-conducting. The impedance, referred to ground, at the point 37 is also relatively low, being of the order of that presented by the detector 34 and its load circuit. The impedances presented to the line 9 and the detector 34 are determined by the positions of the points 31 and 37 respectively.

Under receiving conditions, the tube 39 is non-conducting and has substantially no effect on the operation of the system except that of providing a small shunt capacitance across the resonator. Signals picked up by the antenna 5 are conducted through the lines 3 and 9 to the resonator

37, which functions as a sharply tuned auto transformer to transfer the energy to the detector 34. A portion of the received energy goes to the transmitter 1. This may be minimized if necessary by proper design of the transmitter output circuit.

With each pulse in the output of the pulse source 7, the transmitter 1 provides a corresponding pulse of radio frequency energy, which is conducted to the antenna 5 through the line 3. Simultaneously the pulse voltage is applied to the tube 39 through the connection 43, causing the tube 39 to become conductive.

The upper electrode of the tube 39 is connected to the conductor 17 by the plate 41. The lower electrode is effectively connected to the conductor 19, insofar as the radio frequency energy is concerned, by virtue of concentric line action between the wire 43 and the conductor 19. The open circuit between these two members at the lower end of the conductor 19 is reflected as a short circuit between the upper ends of the wire 43 and the conductor 19.

The impedance of the tube 39 when conductive is so much less than that of the resonator 13 that it acts substantially as a short circuit across the resonator. Also the dielectric constant of the gas in the tube 39 changes with ionization, detuning the resonator to some extent. The impedance presented by the loop 29 to the line 9 is accordingly substantially zero. Since the line 9 is a quarter wavelength long, the short circuit at the one end is reflected as an open circuit at the other end. Thus the line 9 presents a substantially infinite impedance at the point 11, and practically none of the output of the transmitter can flow into the receiver. At the end of each transmitted pulse, the gas in the tube 39 deionizes substantially instantaneously, restoring the system to the receiving condition.

Although a specific embodiment of the invention has been described it is to be understood that the practice of the invention is not restricted thereto, but may be carried out with other apparatus. For example, telegraphic code or voice modulation may be employed instead of pulses. The specific resonator structure shown in Figure 1 may be modified, as shown in Figure 2 by way of example.

Referring to Figure 2, the resonator 13 may be replaced by a quarter wavelength coaxial line comprising an outer conductor 51 and an inner conductor 53, connected together at their lower ends by a disc 55. The inner conductor 53 is tubular, and encloses a coaxially disposed conductor 57, which is connected through a wire 43 to the modulation source, not shown. The upper end of the conductor 57 is connected to one electrode of a glow tube 59. The other electrode of the tube 59 is connected to a disc 61 closing the upper end of the outer conductor 51.

A line 9 extends from the resonator to the antenna system, as in the system of Figure 1, and is coupled to the resonator by a loop 29. A point 37 on the inner conductor 53 is connected through a line 63 to a detector, not shown in Figure 2.

The system of Figure 2 operates in substantially the same manner as that of Figure 1. The inner conductor 53 cooperates with the innermost conductor 57 to act as a quarter wavelength coaxial line, presenting a short circuit for radio frequency energy at its upper end, thus ef-

fectively connecting the lower electrode of the tube 59 to the upper end of the conductor 53.

When the tube 59 is non-conductive, the resonator acts like a transformer between the lines 9 and 63. When the tube 59 is conductive, the resonator presents a short circuit across the line 9.

Thus the invention has been described as an improved method of and means for isolating a receiver from a transmitter connected to a common antenna. This is accomplished by means of a voltage responsive switching device connected between the antenna and the receiver, comprising a resonator and a discharge tube energized by the modulation input to the transmitter.

I claim as my invention:

1. In a radio system including a transmitter, a pulse generator including output terminals connected to said transmitter to modulate the output thereof, an antenna, a transmission line connected from said transmitter to said antenna, and a detector: switching means including a cavity resonator coupled to said detector and having as a wall portion thereof a hollow conductor which terminates within said resonator, a lead-in conductor within and insulated from said hollow conductor and forming therewith a second transmission line having an odd number of quarter wavelengths at the operating frequency open circuited at the other termination of said hollow conductor, a third transmission line an odd number of quarter wavelengths long connected from said resonator to said first transmission line, and voltage responsive discharge means within said resonator and including two electrodes connected respectively to said hollow conductor and said lead-in conductor, said hollow and lead-in conductors being connected to said output terminals of said pulse generator, whereby pulses from the pulse generator may be applied to said electrodes and radio frequency energy at the operating frequency is inhibited from escaping said resonator.

2. A switch device for radio frequency energy, including a cavity resonator comprising an outer conductor, a hollow tubular inner conductor enclosed by said outer conductor and connected at 50 at least one of its ends to said outer conductor, said inner conductor including a longitudinal gap, a voltage responsive gas discharge device including two electrodes positioned at opposite sides of said gap, and a further conductor extending within said tubular conductor and insulated therefrom and connected to one of said electrodes said other electrode being coupled to said cavity resonator outer conductor; coupling means for applying radio frequency power to said resonator; coupling means for absorbing radio frequency power from said resonator, and means for applying a keying voltage between said further conductor and said outer conductor to make said discharge device conductive and effectively short circuit said gap and thereby prevent the transfer of power from one of said coupling means through said resonator to the other of said coupling means, said hollow inner conductor from said gap to said connection to said outer conductor forming with said further conductor a transmission line having an odd number of quarter wavelengths at the operating radio frequency and open-circuited at said one end, thereby to inhibit the escape of radio frequency energy from said resonator at said gap through

said hollow inner conductor at said operating frequency.
